UNITED STATES PATENT OFFICE.

CHARLES E. LUCKE, OF NEW YORK, N. Y.

APPARATUS FOR PREVENTING PULSATIONS IN GAS-MAINS.

1,253,845.

Specification of Letters Patent. Patented Jan. 15, 1918.

Application filed October 28, 1911. Serial No. 657,307.

To all whom it may concern:

Be it known that I, CHARLES E. LUCKE, a citizen of the United States, residing at New York city, county of New York, and State of New York, have invented certain new and useful Improvements in Apparatus for Preventing Pulsations in Gas-Mains, fully described and represented in the following specification and the accompanying drawings, forming a part of the same.

This invention relates to a device for preventing pressure pulsations in gas mains. Much trouble has been experienced from supplying gas engines and especially large one-cylinder engines by direct connections from supply mains which also supply gas for illuminating or other purposes, due to the pulsations in pressure which are set up in the main. These pulsations are frequently of such strength as to damage meters and to cause lights fed from the main not only to pulsate but in many cases to go out. The object of the present invention is to avoid these difficulties by means of a device which will enable gas engines of any size and character, as well as other devices which might produce pulsations in the main if supplied by direct connection from the main, to be supplied from a service main without causing pressure pulsations therein. This result is secured in accordance with the present invention by means of an apparatus or device whereby direct communication between a supply or service main and a branch pipe by which gas is supplied to the engine is prevented, while at the same time a continuous flow to the engine of gas taken from the main is provided at, if desired, substantially the pressure in the main. The invention includes certain features of construction, arrangement and combination of parts in a device of the character referred to and certain details of construction of parts of the same, all as will be herein-after described and specifically pointed out in the claims.

As a full understanding of the invention can best be given by a detailed description in connection with drawings showing a preferred construction embodying the various features of the invention, such a description will now be given in connection with the accompanying drawings, in which—

Figure 1 is a sectional view taken on the line 1 of Fig. 2.

Fig. 2 is a plan view.

Fig. 3 is an enlarged central sectional view of the controlling valve and ports taken on line 3 of Fig. 4.

Fig. 4 is a section taken on line 4 of Fig. 3, but on a somewhat smaller scale.

Fig. 5 is a plan view of the parts shown in Figs. 3 and 4, but with the valve and the cover of the valve chamber removed.

Referring to the drawings, the anti-pulsation device shown is intended to be connected with the gas main by means of a receiving pipe 10, which supplies the gas through a port 11 to a valve chamber 12 in which is mounted a valve 13, which controls the flow of gas from the chamber 12 to one or the other of two gas holders 14 and 15. The valve as shown is a slide valve, and controls not only the flow of the incoming gas from the valve chamber to the containers, but also the flow of gas from the containers to a discharge or delivery pipe 16 leading from the anti-pulsation device to the engine. For this purpose, the valve seat 17 is formed with a central port 18 leading to the pipe 16 and with ports 19 and 20, one on either side of the port 18 and communicating with passages 21 and 22 which lead to the containers 14 and 15 respectively.

The gas containers 14 and 15 may be of any suitable style adapted to expand in receiving gas and to fall or close up for delivering the gas; but bell-type holders such as shown are considered best for the purpose, especially when the device is intended for delivering gas in any considerable quantities. In the approved construction shown, the holders are arranged side by side and spaced sufficiently to permit the valve to be located between them, and each holder is formed of an upper rising and falling part, or bell, 2 having cylindrical sides, and a lower cylindrical shell 3 set on a base 4 formed of a suitable casting or otherwise. The shells 3 are formed with double walls which provide a water-containing space between them in which the cylindrical portion of the bell is adapted to travel, thus providing the usual water seal. Connecting the water space of the two shells is a water chamber or tank 25 of sufficient size to hold a considerable body of water, which serves to maintain the water level in the water space of the shells substantially the same during the rising and falling of the holder bells 2. The bells may be guided in their

rising and falling movement by any suitable means, but for constructions of moderate size the centrally arranged depending rods 26 telescoping in the tubes 27 serve 5 this purpose well while at the same time answering other purposes hereinafter explained. When the weight of the bells is so great that if unbalanced they would deliver the gas under too high pressure, the 10 usual or any suitable counter-balancing devices may be provided, and for maintaining the delivery pressure constant during the whole extent of the downward movement of the bells compensating devices may 15 be provided in the usual manner to compensate for the decrease in pressure due to the side walls of the bells becoming immersed in the water in the water-containing space of the shells as the bells move downward.

The gas passages 21 and 22 formed in the bases 4 of the holders each opens at one end through the base to the interior of the holder, and at the other end opens through 25 the side of the base to connect with one of the valve ports 19 and 20. The body of the valve, formed of a suitable casting or otherwise constructed to provide the valve seat and various ports, as before described, is 30 mounted between and secured to the bases 4 of the holders, and is provided with a removable cover 28. The valve 13 is shifted for changing the connections between the receiving pipe and the delivery or discharge 35 pipe and the two holders by means of actuating rods 30 and 31 mounted to extend through the passages 21 and 22 respectively. The inner end of each rod extends through an opening in the wall of the valve casting 40 in position to engage a suitable abutment on the valve, and the outer end of each rod extends through and is guided by a lug 32, and is connected to the depending arm of a bell crank lever 33 which has an outwardly 45 extending horizontal arm connected to the lower end of the rod 27. The bell crank lever 33 for each holder is conveniently mounted as shown on a bracket 34 secured to the base of the holder over the opening 50 from the passage 21 or 22 into the holder, and this bracket also carries the depending guide lug 32 which guides the end of the valve actuating rod. The rod 26 and tubular rod 27 of each holder are connected in 55 such a way as to permit them to have a relative sliding movement limited to the extent of the desired rising and falling movement of the holder bells, as by having the rods 26 each provided with a pin 35 which pins travel in slots 36 of the tubular rods 27, the slots being of such length that when the bell has reached the limit of its desired upward movement, the pin 35 will have reached the upper end of the slot and will 60 65 act as a stop to limit the further upward

movement of the bell, and that when the bell in descending comes near the desired limit of its downward movement the pin 35 will come into engagement with the lower end of the slot 36 so that a slight continued downward movement of the bell will then throw the bell-crank lever and the valve actuating rod to shift the position of the valve. The outward movement of the valve actuating rods, and consequently the upward movement of the tubular rods 27, is limited by means of stop collars 38 and 39 on the inner ends of the actuating rods.

In order to hold the valve in either position to which it has been shifted, and to insure its quick movement to either position when it has been moved past center by either actuating rod, a weighted throw-arm 40 is mounted within the valve casing to swing on an axis extending transversely 85 of the direction of the movement of the valve, and carries a segment gear 41 which meshes with a rack 42 on the valve. The arm 40 is mounted so that when the valve is in central position the arm will stand 90 vertical, and as the valve is moved in either direction beyond its central position the power of the weight on the arm will be exerted to throw the valve quickly over to the limit of its movement and then to hold the 95 valve in position until it is again shifted past center in the other direction.

The operation is briefly as follows:—With the valve in the position shown in Figs. 1, 3 and 4, the inlet or receiving pipe 10 is in 100 communication through the valve chamber and port 20 and passage 22 with the right hand holder as the apparatus is viewed in Fig. 1, and the discharge pipe 16 is in communication through the valve and port 105 19 and passage 21 with the left hand holder. With the valve in this position, therefore, gas from the supply main will flow into the right hand holder filling the same and causing the bell to rise, and gas from the left 110 hand holder will flow out through the pipe 16 to supply the engine or other consuming apparatus. This will continue until the bell of the left hand holder drops to near the limit of its downward movement, whereupon the actuating rod 30 will be moved to the right to shift the valve to its right hand position. By such shifting of the valve, the left hand roller will be cut off from the discharge pipe 16 and put into communication with the receiving pipe 10, and simultaneously the right hand holder will be cut off from the pipe 10 and put into communication with the pipe 16; and the gas to be 120 consumed will then be supplied from the right hand holder, and the gas from the main will flow into and fill the left hand holder. The operation will thus continue, the valve being periodically shifted automatically and at each shift reversing the 125 130

connections so as to give a continuous supply of gas through the discharge or delivery pipe 16, while at all times preventing any communication between the supply main and the pipe leading to the engine. The transmission to the main of pulsations due to suction of the engine is thus completely and effectually prevented.

It will be seen that the apparatus is well adapted for securing the desired result of preventing transmission of pulsations to the main without reducing materially the pressure under which gas is supplied to the engine. It will be seen further, that the use of a single controlling valve is of great advantage in providing a practical construction whereby the simultaneous shifting of the connections between the two holders and the inlet and discharge pipes is secured, and in avoiding the necessity of careful and accurate adjustment such as is necessary where two or more valves are employed for shifting the connections, and in avoiding adjustment necessitated by wear of operating parts. It is to be noted also that the valve and valve operating parts and connections are all wholly inclosed in gas space of the apparatus, thus avoiding the use of outside operating parts and consequent liability of leakage.

It will be understood that the invention is not to be limited to the exact construction and arrangement of parts of the apparatus as shown in the drawings and to which the foregoing construction has been mainly confined, but that it includes changes and modifications thereof within the claims.

What I claim is:

1. In a device for preventing pulsations in gas mains, the combination of a plurality of independently movable gas receiving and delivering containers, a receiving passage through which gas is supplied from the gas main to the containers, a discharge passage through which gas is discharged from the containers for consumption, a single valve between the receiving passage and the discharge passage and movable for connecting the containers alternately with the receiving passage and the discharge passage and for cutting the containers off from the receiving passage when connected with the discharge passage, said valve being formed to prevent direct communication between the receiving passage and the discharge passage, and means controlled by the last of the closing movement of the containers for operating the valve.

2. In a device for preventing pulsations in gas mains, the combination of a plurality of independently movable gas receiving and delivering containers, a receiving passage through which gas is supplied from the gas main to the containers, a discharge passage through which gas is discharged from the

containers for consumption, passages for connecting the containers with the receiving and discharge passages, a single valve between the receiving passage and the discharge passage for controlling the connection between the receiving and discharge passages and the passages leading to the containers, and means for automatically operating said valve to cause the receiving passage to be connected to one container while gas is being discharged through the discharge passage from another container and to cause the containers to be connected alternately with the discharge passage so as to give a continuous supply of gas through the discharge passage and to be cut off from the receiving passage when connected with the discharge passage, said valve being formed to prevent direct communication between the receiving passage and the discharge passage.

3. In a device for preventing pulsations in gas mains, the combination of two independently movable gas receiving and delivering containers, a receiving passage through which gas is supplied from the gas main to the containers, a discharge passage through which gas is discharged from the containers for consumption, a single valve interposed between the receiving passage and the discharge passage and movable for connecting the containers alternately one with the receiving passage and the other with the discharge passage and vice versa, said valve being formed to prevent direct communication between the receiving passage and the discharge passage, and means controlled by the last of the closing movement of the containers for operating said valve.

4. In a device for preventing pulsations in gas mains, the combination with two independently movable gas receiving and delivering containers, a receiving passage through which gas is supplied from the gas main to the containers, a discharge passage from which gas is discharged from the containers for consumption, controlling means for connecting the containers alternately one with the receiving passage and the other with the discharge passage and vice versa, and operating means controlled by the closing movement of the containers for operating said controlling means, said controlling means and said operating means being mounted wholly within gas-containing space of the apparatus.

5. In a device for preventing pulsations in gas mains, the combination of two independently movable gas receiving and delivering containers, a receiving passage through which gas is supplied from the gas main to the containers, a discharge passage through which gas is discharged from the containers for consumption, connecting pas-

- sages between the containers and the receiving and discharge passages, a valve interposed between the receiving passage and the discharge passage for connecting the containers through the connecting passages alternately one with the receiving passage and the other with the discharge passage and vice versa, and valve operating means mounted within said connecting passages controlled by the closing movement of the containers.
6. In a device for preventing pulsations in gas mains, the combination of two independently movable gas receiving and delivering containers, a valve chamber, a receiving passage through which gas is supplied from the gas main to the valve chamber, a discharge passage through which gas is discharged from the valve chamber for consumption, a connecting passage between each container and the valve chamber, a valve mounted within the valve chamber between the receiving passage and the discharge passage and movable for putting the connecting passages alternately in communication one with the receiving passage and the other with the discharge passage and vice versa, and valve operating devices extending through said connecting passages.
7. In a device for preventing pulsations in gas mains, the combination of two independently movable gas receiving and delivering containers, a valve chamber, a valve seat within the valve chamber having a central port and a port on either side of the central port, an open port or passage leading to the valve chamber, said central port and said open port being connected one to receive the gas from the main and the other to discharge gas for consumption, a connecting passage leading from one container to one of said side ports, and a connecting passage leading from the other container to the other of said side ports, a valve movable on said valve seat between the central port and said open port to connect the side ports alternately one with the central port and the other with the interior of the valve chamber and vice versa, and valve shifting means controlled by the closing movement of the containers.
8. In a gas supply system, the combination with a supply main, of a receiving passage leading from the main, a discharge passage through which gas is supplied for consumption, and means interposed between the receiving passage and the discharge passage for maintaining a supply of gas in the discharge passage while preventing the transmission of pulsations from the discharge passage back through the receiving passage to the main, said means comprising a plurality of gas receiving and delivering containers and flow-controlling means for connecting the containers alternately with the receiving passage and the discharge passage and means for operating said flow-controlling means to give a continuous supply of gas to the discharge passage, said flow-controlling means being formed to at all times cut off communication between the receiving passage and the discharge passage.
- In testimony whereof, I have hereunto set my hand, in the presence of two subscribing witnesses.

CHARLES E. LUCKE.
